(57) CLAIM

The ornamental design for a women's billiards glove, as shown and described.

DESCRIPTION

FIG. 1 is a plan view of a women's billiards glove showing my new design.

FIG. 2 is a bottom view of the glove.

FIG. 3 is a right side elevation view of the glove; and,

FIG. 4 is a left side elevation view of the glove.

The broken line showing a hand in FIGS. 1-4 is for illustrative purposes only and forms no part of the claimed design.

1 Claim, 4 Drawing Sheets

FIG. 1

FIG. 4
